UNITED STATES PATENT OFFICE.

JACOB P. PLATTENBERGER, OF SAVANNA, ILLINOIS.

FENCE-POST.

SPECIFICATION forming part of Letters Patent No. 758,778, dated May 3, 1904.

Application filed February 8, 1904. Serial No. 192,553. (No model.)

To all whom it may concern:

Be it known that I, JACOB P. PLATTENBERGER, a citizen of the United States, residing at Savanna, in the county of Carroll and State 5 of Illinois, have invented new and useful Improvements in Fence-Posts, of which the following is a specification.

This invention relates to fence-posts molded of concrete or other plastic material, and has 10 for its object to provide an improved post characterized particularly by improved means for fastening the line-wires to the post, as will more fully hereinafter appear.

In the accompanying drawings, Figures 1 15 and 2 are respectively front elevation and longitudinal section of the post.

The body of the post is indicated at 6, molded to the desired shape, of concrete or similar plastic material, and having embedded and extending lengthwise therein from one end to the other a metal strengthening-rod 6^a. A strip 10 is molded in the post at the time it is made. This strip is partially embedded in the concrete and extends from the top of the 25 post to the ground-line thereof. It is preferably formed of metal, and the projecting edge is notched, as at 11, forming a series of places to receive line-wires, (indicated at 12.)

The strip is cast or made with a large number 30 of notches, so that it may be used on posts to which various numbers of line-wires are to be attached. The number of wires desired is determined before the posts are cast, and corre-

sponding holes are cored through the post, as indicated at 9^a. In stringing the wires they 35 are placed in the notches at the holes, and tie-wires 13 are then passed through the post over the line-wires and strip and fastened at the back, as by wedges 15, driven in the holes. These tie-wires hold the line-wires in place 40 against the strip and also serve to bind the strip in place. This method of attachment and support permits barb-wires to be used and to be readily attached to the post, and the wires may be strung with much more facility than with those posts having holes through which wires are strung. The invention 45 also permits quick replacing of any wire or the stringing of additional wires if and when it becomes desirable.

What I claim as new, and desire to secure by Letters Patent, is—

A molded fence-post having holes therethrough, a strip for attachment of line-wires, partly embedded in the post in line with the 55 holes, tie-wires extending around the strip and through the holes, and wedges plugged in the holes to fasten the tie-wires therein.

In testimony whereof I have signed my name to this specification in the presence of two sub- 60 scribing witnesses.

JACOB P. PLATTENBERGER.
